UNITED STATES PATENT OFFICE.

HENRY M. PIERSON, OF BROOKLYN, NEW YORK.

MANUFACTURE OF GAS.

SPECIFICATION forming part of Letters Patent No. 392,458, dated November 6, 1888.

Application filed February 3, 1888. Serial No. 202,868. (No model.)

To all whom it may concern:

Be it known that I, HENRY M. PIERSON, of Brooklyn, in the county of Kings and State of New York, have invented an Improvement in 5 Manufacturing Gas; and the following is declared to be a full and complete description of the same.

In my present improvements I make use of a generating-furnace into which incandescent coke is introduced periodically, and it is fired up from time to time to intensify the heat by blowing air through it, and steam is passed through the incandescent fuel and is decomposed and forms a non-luminous or water gas, 10 with which a small quantity of olefiant gas is commingled from a small quantity of hydrocarbon liquid supplied into the chamber, the blast of air being shut off during the gas-making operation. The heat and heated gases pass up 15 into a chamber containing retorts, into which retorts bituminous coal is introduced from time to time, and the olefiant gas distilled from the same passes off to a peculiarly-constructed hydraulic main, in which the tarry products are 20 condensed and pass into tanks, and the gases pass into a retort containing loose refractory material, which retort is also in the retort-chamber, and into this retort steam is admitted to combine with the olefiant gas and form 25 non-luminous or fuel gas, and the gases from the two sources named pass to one washer and commingle, and the coke, as it is drawn from the respective retorts, is delivered in its incandescent condition into the generating-furnace and the tar is burned to aid in heating 30 the retort-chamber.

By combining in one apparatus the devices for making non-luminous gas by the two methods named I am enabled to economize the production of non-luminous gas from bituminous coal, and at the same time avoid the risk here- 40 tofore existing from the non-luminous gas made from anthracite coal, because such non-luminous gas is of the most deadly character when inhaled and is nearly inodorous, while in the gas made by my improvement there is sufficient olefiant gas present to scent the non-luminous gas and lessen the risk of the same being inhaled without being noticed.

50 In the drawings I have shown the apparatus

especially designed by me for the manufacture of non-luminous gas from bituminous coal, wherein—

Figure 1 is a vertical section of most of the apparatus, portions being in elevation. Fig. 55 2 is a vertical cross-section at the line *xx* of Fig. 1, and Fig. 3 is a side elevation of a hopper and its carriage.

A represents the generating-furnace, which is of usual character and in which there is an 60 air-tight door, *a*, opening into the ash-pit for the removal of ashes, an air-blast pipe, *b*, with a regulating-gate, *b'*, and a steam-pipe, *c*, providing for the inlet of air and steam, a throat, *d*, and gas-tight cover *d'* providing for 65 the admission of fuel.

B represents the retort-chamber, which is located above the generating-furnace, the interior of which chamber is connected with the generating-furnace by the throat *e*, and there 70 is a chimney, *D*, and tight-fitting valve *f* within the same on top of the retort-chamber, by which the products of first combustion or heating up are passed off.

There is an air-blast pipe, *b*, having a regulating-gate, *b'*, and this air-blast pipe is connected to and rises from the pipe *b*, and its upper end passes around and is continued as a flue, *b'*, in the front wall of the retort-chamber B, and air is admitted through this pipe *b* and 75 *b'* into the retort-chamber, where it combines with the unconsumed gases issuing from the throat *e* during the heating-up operation, and the combustion of the said gases is thereby made perfect or more complete by the additional quantity of air thus admitted.

The retorts *g h i k* for bituminous coal are of the usual character, and they rest in or against the back wall of the chamber and pass through the front wall and are provided with 90 covers *l*, by which said retorts are charged with bituminous coal and the coke discharged therefrom, and there are pipes *g' h' i' k'* (shown in Fig. 2 by dotted lines) connected with said retorts outside the chamber B, and these pipes 95 pass upwardly and over into the hydraulic main C, and their lower ends can be sealed within said main, as hereinafter described. This hydraulic main is supported upon the retort-chamber in any desired manner.

Within the hydraulic main C and beneath the lower end of each pipe g' h' i' k' are metal pans or cups 5, and said pans are supported and guided in their position by the pairs of vertical rods 6 7, which are united to said pans and pass up through stuffing-boxes in the upper shell of the hydraulic main and are connected at their upper ends by the cross-heads 8, to each of which is connected a rope or chain, 10 9, which by preference passes away over a pulley to a point easily accessible, where it can be made fast. These pans 5 are filled with tar and other such products of the distillation of bituminous coal, as is also the bottom of the 15 hydraulic main, as hereinafter more fully described, and the lower ends of these pipes g', h', i', and k' come just above the tar in said pans, and said pans can be elevated by the rods 6 7 and chains 9 until the surface of the bottom of 20 said pans comes against the end of said pipes and closes them completely. The object of thus closing the ends of the pipes g', h', i', and k' is to be able to draw the coke from any one of the retorts without risk of the gas in the other retorts backing up and burning or exploding in 25 the retort that happens to be open.

Connected to the respective ends of the hydraulic main C are the pipes u u', bent, as shown, to form traps, and opening into the 30 tar-tanks v v'; and there are pipes w w' connected to the bottom of said tanks and passing downward and into opposite sides of the retort-chamber, and said pipes w w' are provided with cocks 10, and within the retort-chamber there 35 are inclined tables y y. The hot tarry products deposited in the hydraulic main C pass by the pipes u u' into the tanks v v' and by the pipes w w' within the retort-chamber and are delivered upon the inclined tables y y, for the purposes hereinafter more fully described.

The retort m, which constitutes the salient feature of my invention, is preferably of oval form in cross-section and extends entirely through the retort-chamber, having a cover at 45 each end, and the same contains loose refractory material, as shown. A pipe, n, connects one end of this retort with the hydraulic main C, and this pipe n simply enters the top of said main. There is a pipe, o, connected to the 50 other end of the retort m, and the same passes into and seals within the washer E, and there is a pipe, p, connected to the top of the retort-chamber B, which also passes to and seals within the washer E, and there is a pipe, o', 55 passing from the washer E away to a holder. There is a steam-pipe, r, entering the forward end of the retort m, as shown, and a pipe, s, entering the retort-chamber R, by which a hydrocarbon liquid is conveyed within said 60 chamber. Any number of retorts for bituminous coal may be used.

I have shown rails 1 2, forming a track across the top of the generating-furnace, and in Fig. 3 I have shown a hopper or chute, t, and its carriage upon the rails 1 2, by which I discharge the coke from the retorts into the gen-

erating-furnace, and in Fig. 2 the chute is shown by dotted lines as capable of discharging the coke from any or all of the retorts without shifting its position.

The operation of carrying on the manufacture of gas is as follows: The generating-furnace is first charged with coke or other fuel and fired, and the retorts g h i k are charged with bituminous coal and sealed.

The air blast is then admitted into both generating-furnace and retort-chamber by the pipes b and b', and the blowing up is continued until the fuel in the generating-furnace is raised to a point of incandescence, the issuing gases mean-

while passing through the throat e into the retort-chamber B, where a perfect combustion takes place in and around the retorts g, h, i, k, and m, because of the extra quantity of air entering by the flue b', and the said retorts are heated up to a high temperature and the products of combustion pass away by the chimney D, the cover f of which had been previously removed.

The air is then shut off at the gates b' and b'', and the cover f closed to its seat, and steam under pressure is admitted into the generating-furnace by the pipe c, and passes

through the fire and is decomposed into hydrogen, (H), about fifty per cent., carbonic oxide, (CO), about forty per cent., and about ten per cent. of carbonic acid, (CO₂), the constituents of water-gas.

At this time a hydrocarbon liquid is admitted through the pipe s into the heated retort-chamber B, and becomes converted into olefiant gas, and as the water-gas passes into and through the retort-chamber an element of carbon from said olefiant gas combines with the oxygen of the carbonic acid, (CO₂), forming CO, or carbonic oxide, thereby doubling its volume and reducing all, or nearly

all, the gases to hydrogen and carbonic oxide or non-luminous gas, which passes by the pipe p from the retort-chamber over into the washer E and by the pipe o' to any suitable holder.

As water-gas is practically odorless, it is difficult to detect its presence in an apartment or when escaping from pipes, and I provide for a slight surplus of olefiant gas from the conversion of the acid in order that the same may commingle with the non-luminous gas and impart to

it a scent or distinctive odor, which will make it possible to detect its presence and lessen the risk of the gas being inhaled without being noticed.

While this operation of blowing up the generating-furnace and making water-gas is being carried on and simultaneously therewith the bituminous coal in the heated retorts g h i k is undergoing distillation, and the rich coal-gas (illuminating-gas) and vapors, oils, and other products evolved from this distillation

pass by the pipes g' h' i' k' up and into the hydraulic main C. The heavier products of decomposition and distillation—such as tar, oils, &c.—are retained in the hydraulic main and gradually displace the water, which the heat

vaporizes, while the gases pass out (see arrows in Figs. 1 and 2) by the pipe n downwardly

into the oval-shaped retort *m*, containing refractory material, in which it meets the incoming steam from the pipe *r*, which steam, as it passes through the highly-heated retort in company with the illuminating-gas, is decomposed by the carbon of the illuminating-gas combining with the oxygen of the steam, forming carbonic oxide (CO) and setting free the hydrogen, thus forming the component parts of non-luminous or fuel gas, and these gases so formed pass by the pipe *O* at the opposite end of the retort *m* into and through the washer *E* and by the pipe *o'* to a suitable holder, which by preference is the same holder that receives the gas passing by the pipe *p*. Meanwhile the hot tar, oils, and heavy products of combustion deposited in the hydraulic main fill the pans 5 and flow over and fill the lower part of the hydraulic main to a level with the edge of the pans, and the surplus overflows by the trapped pipes *u u'* into the tar-tanks *v v'* and fills the vertical pipes *w w'*, and during the heating-up process in the generating-furnace *A* and retort-chamber *B*, I discharge some of this hot tar, &c., through the cocks 10 within the retort-chamber onto the inclined tables 7, where the tar burns by the excess of air purposely admitted by the pipe *b²* and flue *b⁴*, and this greatly assists the heating-up process, bringing the retorts up to a very high temperature, besides effecting economy in the gas-making operation. The coke contained in these retorts *g h i k* at the completion of these operations is discharged by means of the hopper *t* into the generating-furnace *A* through the throat *d* to replenish its fire, after which these retorts are recharged with bituminous coal, the coke in the generating-furnace is blown up to incandescence, and the gas-making operations repeated, as heretofore described.

My method differs essentially from those in use previously in that while I am blowing up the generating-furnace to incandescence and afterward making non-luminous gas from the decomposition of steam and the addition of olefiant gas made from hydrocarbon liquid I am also decomposing bituminous coal and making illuminating-gas, which I convert by steam

into non-luminous gas in a separate retort containing refractory material, the coke left from this last portion of the process being utilized as a fuel afterward in the generating-furnace.

I claim as my invention—

1. The combined methods herein specified of making heating-gases from bituminous coal, consisting in distilling the coal and passing the resulting gas through a heated retort containing refractory material and into which steam is admitted and passing the coke from such retorts in an incandescent condition into a generating-furnace, blowing up such coke to intensify the combustion, and simultaneously heating the retorts by the escaping products and then passing steam through the incandescent coke when the supply of air is shut off, so as to decompose the steam in the presence of the carbon of the coke and form a heating-gas, and conveying the heating-gases from the two sources to a holder, where they are mixed, substantially as specified.

2. The combined methods herein specified of making heating-gases from bituminous coal, consisting in distilling the coal and passing the resulting gas through a heated retort containing refractory material and into which steam is admitted and passing the coke from such retorts in an incandescent condition into a generating-furnace, blowing up such coke to intensify the combustion, and simultaneously heating the retorts by the escaping products and then passing steam through the incandescent coke when the supply of air is shut off, so as to decompose the steam in the presence of the carbon of the coke and form a heating-gas, and introducing liquid hydrocarbon, the gas from which combines with any carbonic acid present and forms carbonic oxide, and also gives to the non-luminous gas an odor, for the purposes set forth, and conveying the heating-gases from the two sources to a holder, where they are mixed, substantially as specified.

Signed by me this 20th day of January, A. D. 1888.

H. M. PIERSON.
